UNITED STATES PATENT OFFICE

JOHN F. HALLADAY, OF RIVER FOREST, ILLINOIS, ASSIGNOR TO CONTAINER CORPORATION OF AMERICA, OF CHICAGO, ILLINOIS, A CORPORATION OF DELAWARE

TRAY

Application filed November 22, 1930. Serial No. 497,400.

The invention relates to trays composed of paper, paper board or like flexible material, particularly adapted for holding bread and similar edible products. The object of the invention is to provide a simple tray which may be manufactured at low cost, and which may be shipped flat in a collapsed condition, and which, when arrived at its destination, may be readily set up to receive the desired article, such as a loaf of bread.

According to the preferred embodiment of my invention, the tray may be formed from a single blank, which may be readily formed into a box or tray adapted to be shipped flat, and which may be set up by merely pushing inwardly on the end walls, thereby opening up the side walls, whereupon locking flaps, preferably formed integral with the end walls, are folded inwardly over the end walls, thereby holding the box in assembled or set up position. The locking flaps are readily operated by a simple folding operation, and firmly hold the box in assembled position without the necessity for fitting tabs into slots, or the employment of complicated fastening means, and may be as readily opened up to again permit collapsing of the tray. The collapsing operation is made possible by diagonal scoring of the end flaps. The locking flaps, when infolded, brace the end flaps to prevent bending along the diagonal lines, but when the locking flaps are opened up, the bracing effect is removed and the box may then be collapsed along the lines of weakness. While according to the herein disclosed embodiment of the invention, the ends of the tray are diagonally scored and the locking flaps applied thereto, it is obvious that a similar arrangement might be applied to the sides of the tray. Accordingly, in the present specification it will be understood that the terms "ends" and "sides" may be interchanged one for the other, as referring to opposite walls of the tray.

The invention will be more readily understood by reference to the accompanying drawing and the following detailed de-

scription setting forth an illustrative embodiment, it being understood that the details may be varied without departing from the spirit of the invention.

In the drawing, 55
Fig. 1 is a perspective view of the tray showing one locking flap folded in place to hold the tray in assembled position and showing the other locking flap open preparatory to infolding;

60
Fig. 2 is a fragmentary view showing one-half of the blank from which the tray is prepared, the other half being broken away; and

65
Fig. 3 is a plan view showing the tray collapsed for shipping, one of the locking flaps being shown as folded inwardly and the other extending outwardly to illustrate two positions in which the box may be shipped;

70
The tray may be formed from paper, paper board, or other suitable flexible material, and is preferably manufactured from a single blank which may be cut away in one stamping operation and suitably scored 75 to provide hinged flaps by means of which the blank may be assembled into the form of a tray. The blank is shown fragmentarily in Fig. 2 and since both ends of the tray are alike, one end only is shown in the figure. 80

85
The blank comprises a bottom portion 10 having sides 11 hinged thereto along flexible lines 12. Ends 13 are hinged to the bottom portion along flexible lines 14, these ends being provided with side extensions or flaps 15, which are adapted to be folded inwardly along lines 16 and pasted to the sides 11 when the box is assembled. The flaps 15 are preferably separated from the sides 11 by suitable cut-away portions 17, 90 herein shown as straight at the edges of the sides 11 and as flaring at the edges of the flaps 15. The purpose of the cut-away portions is to facilitate folding and assembling of the box. Extending beyond the ends 13 are locking flaps 18, preferably of the same length and width as the ends 13 to which they are joined along flexible lines 19. Extending inwardly from the ends of the score lines 19 are diagonal slits 20. From the 95

inner ends of the slits 20 diagonal score lines 21 extend outwardly to points 24, where the score lines 12 and 14 join. The purpose of the diagonal slits 20 and score lines 21 is to facilitate collapsing of the tray, as will be apparent hereinafter.

To form the blank into a tray or box, the sides 11 are folded upwardly along the score lines 12, the ends 13 are folded upwardly along the lines 14 and flaps 15 are folded inwardly along lines 16. The flaps 15 are then glued to the sides 11, as clearly indicated in Fig. 1.

The box may be collapsed for shipment in the form shown in Fig. 3. The collapsing is accomplished by pressing the ends 18 outwardly, causing the triangular portions 22 thereof to fold inwardly along diagonal lines 21, the triangular portions being separated from the remainder of the end flaps along the slits 20. Folding the ends 18 outwardly draws the sides 11 inwardly by reason of the connection between the two through the glued flaps 15. The locking flaps 18 may be either folded outwardly as indicated at the right in Fig. 3, or folded over the ends 13, including the triangular portions 22, as indicated at the left in Fig. 3.

Obviously the containers may be shipped in large quantities and occupy a minimum of space when collapsed in the manner shown in Fig. 3. When the trays have arrived at their destination they may be assembled for use by merely pressing upwardly and inwardly on the end walls 18, forcing the side walls 11 outwardly. The tray may then be locked in assembled position by folding the flaps 18 inwardly so as to overlap the ends 13, covering the diagonal slits 20 and score line 21, thus preventing collapsing along these weakened lines. It will be noted that the locking flap 18 extends the full length and width of the end 13, so that a reinforcement along its entire area is provided. The flaps 18 fit in position, and due to the added thickness caused by the glued flaps 15, a slight outward pressure is exerted on the sides of the box. Thus when once the flaps 18 have been folded into locking position, there is no tendency for them to again fly open, although they may be readily opened manually. Consequently no tabs and slots are required in order to retain the parts in assembled relation. A loaf of bread or other like article may now be readily inserted within the tray.

The locking flaps 18 constitute one of the important features of the invention. They are preferably of such dimensions as to frictionally engage both the sides and bottom of the container, when infolded in locking position. This frictional engagement is sufficient to retain the flaps in the locking position and to maintain the container upright until the locking flaps are manually released.

The frictional engagement with the side walls of the container is increased by the added thickness of the glued flaps 15.

While in the above described embodiment of the invention the diagonal score lines are provided in the ends 18 and the locking flaps are provided as extensions thereof, it is obvious that a similar arrangement could be provided on the sides 11 without departing from the spirit of the invention.

What I claim is:

1. A collapsible tray comprising a bottom, and side and end walls hingedly secured to the bottom, securing flaps hingedly connected to the end walls and glued to the side walls, diagonal score lines extending from the ends of the lines of juncture between the bottom and ends partially across the end walls, and diagonal slits extending from the ends of the score lines outwardly to the edges of the end walls, whereby the tray may be collapsed along the diagonal score lines by pressing outwardly on the end flaps, and means for locking the tray in upright position comprising locking flaps hingedly connected to the end walls and of equal length and width with the end walls, said locking flaps when infolded completely overlapping the scored and slitted portions of the end walls and serving to reinforce the same, to prevent collapsing and at the same time preventing infolding of the side walls.

2. A collapsible tray comprising a bottom, and side and end walls hingedly secured to the bottom, securing flaps hingedly connected to the end walls and glued to the side walls, diagonal score lines extending from the ends of the lines of juncture between the bottom and ends partially across the end walls, and diagonal slits extending from the ends of the score lines outwardly to the edges of the end walls, whereby the tray may be collapsed along the diagonal score lines by pressing outwardly on the end flaps, and means for locking the tray in upright position comprising locking flaps hingedly connected to the end walls and of equal length and width with the end walls, said locking flaps when infolded completely overlapping the scored and slitted portions of the end walls and serving to reinforce the same, to prevent collapsing and at the same time preventing infolding of the side walls, the locking flaps being retained in locking position by friction alone.

3. A collapsible tray comprising a bottom, and side and end walls hingedly secured to the bottom, securing flaps hingedly connected to the end walls and glued to the side walls, diagonal score lines extending from the ends of the lines of juncture between the bottom and ends partially across the end walls, and diagonal slits extending from the ends of the score lines outwardly to the edges of the end walls, whereby the

- tray may be collapsed along the diagonal score lines by pressing outwardly on the end flaps, and means for locking the tray in upright position comprising locking flaps 5 hingedly connected to the end walls and of equal length and width with the end walls, said locking flaps when infolded completely overlapping the scored and slitted portions of the end walls and serving to reinforce the 10 same, to prevent collapsing and at the same time preventing infolding of the side walls, the locking flaps when in locking position frictionally engaging the sides of the tray.
4. A collapsible tray comprising a bottom, and side and end walls hingedly secured to the bottom, securing flaps hingedly connected to the end walls and glued to the side walls, diagonal score lines extending from the ends of the lines of juncture between the bottom and ends partially across the end walls, and diagonal slits extending from the ends of the score lines outwardly to the edges of the end walls, whereby the tray may be collapsed along the diagonal score lines by pressing outwardly on the end flaps, and means for locking the tray in upright position comprising locking flaps hingedly connected to the end walls and of equal length and width with the end walls, said locking flaps when infolded completely overlapping the scored and slitted portions of the end walls and serving to reinforce the same, to prevent collapsing and at the same time preventing infolding of the side walls, the locking flaps being retained in locking position by frictional engagement with the sides and bottom of the tray.
5. A collapsible tray comprising a bottom, and side and end walls hingedly secured to the bottom, securing flaps hingedly connected to the end walls and glued to the side walls, diagonal score lines extending from the ends of the lines of juncture between the bottom and ends partially across the end walls, and diagonal slits extending from the ends of the score lines outwardly to the edges of the end walls, whereby the tray may be collapsed along the diagonal score lines by pressing outwardly on the end flaps, and means for locking the tray in upright position comprising locking flaps hingedly connected to the end walls and of equal length and width with the end walls, said locking flaps when infolded completely overlapping the scored and slitted portions of the end walls and serving to reinforce the same, to prevent collapsing and at the same time preventing infolding of the side walls, the locking flaps when in locking position frictionally engaging the bottom of the tray.
6. A collapsible tray comprising a bottom, and side and end walls hingedly secured to the bottom, securing flaps hingedly connected to the end walls and glued to the side walls, diagonal score lines extending from the ends of the lines of juncture between the bottom and ends partially across the end walls, and diagonal slits extending from the ends of the score lines outwardly to the edges of the end walls, whereby the tray may be collapsed along the diagonal score lines by pressing outwardly on the end flaps, and means for locking the tray in upright position comprising locking flaps hingedly connected to the end walls and of equal length and width with the end walls, said locking flaps when infolded completely overlapping the scored and slitted portions of the end walls and serving to reinforce the same, to prevent collapsing and at the same time preventing infolding of the side walls, the locking flaps when in locking position frictionally engaging the said securing flaps.
7. A collapsible tray comprising a bottom, side and end walls hingedly secured thereto, means for connecting the adjacent ends of said end and side walls when the box is in upright position, diagonal score lines extending from the ends of the lines of juncture between the bottom and end walls partially across said end walls, slits extending from the ends of the score lines outwardly to the edges of the end walls, whereby the tray may be collapsed along the diagonal score lines by pressing outwardly on the end walls, and means for locking the tray in upright position, said means comprising locking flaps hingedly secured to the end walls and adapted to be folded inwardly to overlap the scored and slitted portions of the end walls and be frictionally held in place.
8. A collapsible tray comprising a bottom, side walls, and at least one end wall hingedly secured to said bottom, means for securing the adjacent ends of said side walls and said end wall when the tray is in upright position, diagonal score lines extending from the ends of the line of juncture between the bottom and said end wall partially across said end wall, slits extending from the ends of the diagonal score lines outwardly to the edge of said end wall, whereby said tray may be collapsed along the diagonal score lines by pressing outwardly on said end wall, and means for locking the tray in upright position, said means comprising a locking flap hingedly secured to said end wall and adapted to be folded inwardly to overlap the scored and slitted portions of said end wall.

Signed at Chicago, Illinois this 19th day of November, 1930.
